UNITED STATES PATENT OFFICE.

FRANK P. MONTGOMERY, OF SAN JOSE, CALIFORNIA.

MAP-RACK.

SPECIFICATION forming part of Letters Patent No. 316,905, dated April 28, 1885.

Application filed March 12, 1884. (No model.)

To all whom it may concern:

Be it known that I, FRANK P. MONTGOMERY, a citizen of the United States, and a resident of San José, in the county of Santa Clara and State of California, have invented 5 certain new and useful Improvements in Map-Racks; and I do hereby declare that the following is a full, clear, and exact description of the invention, which will enable others skilled in the art to which it appertains to 10 make and use the same, reference being had to the accompanying drawings, which form a part of this specification, and in which—

Figure 1 is a front view of my improved adjustable map-rack, showing the same extended 15 to its greatest width. Fig. 2 is a front view, showing the rack adjusted to about one-half of its entire width; and Fig. 3 is a perspective view of the rack, showing it adjusted to about 20 two-thirds of its entire width.

Similar letters of reference indicate corresponding parts in all the figures.

My invention consists in the improved construction and combination of parts of an adjustable map-rack, as will be hereinafter more 25 fully described, and particularly pointed out in the claims.

In the accompanying drawings, A A' represent 30 the rear uprights of the rack, one of which, A', is secured to a suitable bearing or support, a. The upper cross piece of the rear frame consists of a tubular rod, B, extending horizontally from the upper end of the upright A', and a rod, B', extending from the upper 35 end of the upright A, and of such a size as to fit and slide within the tubular rod B, the parts B and B' being of about the same length. The free end of the tubular rod B is supported against a suitable support or bearing, b, by a 40 staple, c.

The lower ends of the uprights A and A' are 45 adjustably connected by means of a tubular rod, C, and rod C', adapted to slide within the tube C, these lower rods also passing through the lower ends of the side pieces of the front frame of the rack within which the maps are supported. The upper ends of these side pieces, D D', are adjustably connected by 50 means of a tubular rod, E, and a rod, E', sliding within the same. The various tubular rods, which are similar in construction, are provided with thumb-screws d, by means of

which the various sliding rods are secured firmly in their adjusted position.

F indicates an adjustable side piece, which 55 slides upon the tubular rods C and E, being held in its adjusted position by means of suitable thumb-screws, f, a number of bearings, G, being secured upon the inner side of the said sliding piece and the inner side of the upright D, for the purpose of receiving the ends of self-acting spring-rollers H, of ordinary construction, upon which rollers the maps are mounted.

I indicates a cord or wire which is fastened 60 at one end to the upper portion of the hinged part of the rack, passes over the upper horizontal tube, B, and has secured upon its lower free end a weight, I', of sufficient weight to hold the rack in its closed position.

The upper ends of the side pieces of the front and rear frames of the rack are connected by springs J J, the construction of 65 which is more clearly shown in Fig. 3 of the drawings, the said springs serving to open the rack when the weight I' is lifted from below, and also serving to hold the hinged parts of the rack together in case the cord I should accidentally slip or break.

K represents a curtain which is supported 70 upon an automatic spring-roller, K', and is of such a size that when pulled down it will entirely cover and shield the map-rack and the maps and charts thereon from dust, dirt, &c.

From the foregoing description, taken in 75 connection with the accompanying drawings, the construction of my improved adjustable map rack will readily be understood without requiring further explanation.

It will be seen that by constructing the 80 various parts of the rack in the manner described the width of the rack may be adjusted to adapt it to fit or receive maps or charts of any width—say from twenty-six to one hundred inches—while by means of the slide F the most delicate adjustments may be effected without disturbing the entire rack.

By means of the cord I, weight I', and 85 springs J J the rack can be opened or closed from the ground without having to mount 90 upon a chair or step-ladder.

Having thus described my invention, I claim and desire to secure by Letters Patent of the United States—

1. The combination, with the uprights A A' and D D', of the adjustable cross-pieces or connections B B', C C', and E E', each cross-piece consisting of a tubular rod and a solid rod adapted to slide within the tubular rod, as set forth.
2. The combination, with the uprights A A' D D' and adjustable connections B B', C C', and E E', of the springs J J, operating-cord 10 I, and weight I', by means of which the map may be automatically opened or closed, as set forth.
3. The combination of the uprights A A' and D D', adjustable connections B B', C C',

and E E', constructed as described, sliding 15 pieces F, moving adjustably upon the tubular rods C and E, springs J J, operating-cord I, and weight I', all constructed and arranged to operate substantially in the manner and for the purpose shown and described. 20

In testimony that I claim the foregoing as my own I have hereunto affixed my signature in presence of two witnesses.

FRANK P. MONTGOMERY.
